HOLDER OR STAND FOR PINS

Frank Ostrander, London, England

Application December 23, 1932, Serial No. 648,709
In Great Britain April 30, 1932

5 Claims. (Cl. 223—60)

This invention relates to holders or stands for pins and has for its object to provide holders by which a straight row of pins can be held vertically or slightly inclined in a stand on a table and presented in a convenient manner to enable a pin to be readily withdrawn without disturbing the remainder of the pins in the holder.

According to the invention, the improved holder comprises a carrier consisting of two plates spaced apart and arranged so as to retain a straight row of pins between them with their heads projecting clear of the carrier the front plate of the carrier being provided with projections at its upper edge extending towards the back plate and adapted to engage with the projecting fold of a paper carrying the pins whereby the paper is held between the plates without interfering with the ready withdrawal of the pins, and preferably a base to which the carrier is detachably or permanently attached whereby said carrier may be supported from a table in a vertical or slightly inclined plane with the heads of the pins presented uppermost.

In one form, the carrier is made of metal plates adapted to retain and hold in position a single row of pins threaded in paper as ordinarily sold. In one form one of the plates forms a back plate and its lower portion is turned, rolled or otherwise thickened so that it can be engaged in a groove in the base, and the front plate is arranged to clamp the paper of pins against the back plate. For this purpose the front plate may have an edge turned over to engage with one edge of the back plate and the other end of the plate is formed with a spring clip or rolled over so that it can be readily sprung over the corresponding edge of the back plate, thus firmly clamping the paper of pins in position. The front plate is provided along its top edge with projections which are turned over so as to engage with the fold of the paper through which the pins are thrust. By this means when a pin is extracted the paper with the remaining pins will be firmly held in position. At the same time the pins will not be gripped between the plates to hinder the easy withdrawal of the pins.

Pins are very often sold in sheets containing five, six, or in some cases ten, parallel rows of pins thrust through folds in the paper. Bearing this in mind, in another form of carrier according to the invention the lower part of the carrier, which may be attached or held in a suitable base, or which may itself form the base of the stand, is constructed as a box to hold

such a paper of pins with the uppermost row projecting through a slot in the top of the box so as to be retained between the front and back plates of the carrier as in the example last described.

It is convenient in a pin holder such as described in order to enable a single pin to be more readily extracted that the heads of the pins should not be presented in a straight level row, but should form a wavy or zigzag line so that adjacent heads will be uneven or at different elevations. To cause the pins to take such a position in the carrier, the front plate may be provided on its rear side adjacent its lower edge with a projection of wavy or zigzag profile to engage with the points of the pins when adjusting the front plate thereon so as to force the heads of some of the pins upwards through the paper.

In order that the nature of the invention may be more clearly understood I have shown in the accompanying drawings how it may be carried out in practice in various ways by way of example.

In said drawings:—

Fig. 1 is a perspective view showing a carrier formed of metal plates adapted to hold in position a paper containing a single row of pins as commonly sold.

Fig. 2 is a vertical cross-sectional view of the carrier shown in Fig. 1 drawn to an enlarged scale.

Fig. 3 is a view of the rear face of the front plate of the carrier shown in Fig. 1 showing the projection for causing the heads of the pins to assume a wavy line.

Fig. 4 is a perspective view of a holder comprising a carrier similar to that shown in Fig. 1 but in which the back plate of the carrier is formed integral with the base.

Fig. 5 is a perspective view of a holder provided with a carrier having at its lower portion a box or magazine adapted to hold a number of rows of pins, and

Fig. 6 shows a form of blank from which the back plate and magazine shown in Fig. 5 may be constructed.

Referring now to Figs. 1 to 3, the base 1 has an undercut groove 9 of circular cross-section providing a slot in the upper face of the base. The carrier is formed of two metal plates, one of which, 10, constitutes the back plate and the other, 11, the front plate. The back plate has its lower edge rolled, as shown at 12, to fit the groove 9 in the base. The front plate is detachably held applied to the back plate by its end 110

edges, one of which is bent over as indicated at 13, and the other of which is bent over as shown at 14 so as to form in effect a spring clip. After the folded edge 13 of the front plate has been engaged with the corresponding edge of the back plate 10 the rounded bent over clip portion 14 of the front plate can be sprung over the corresponding edge of the back plate, thus firmly clamping the two plates together. Fig. 2 shows a paper 15 having folds 16 in which the pins 6 are thrust, and also shows teeth 17 on the front plate 11 which are turned over and which, when the plates are clamped together, engage with one of the 20 folds 16 (the lower fold as shown, for example, in the drawings) of the paper holding the pins.

Fig. 3 shows the arrangement whereby the heads of the pins may be caused to assume a wavy line. The back face of the front plate 11 is provided with a projection having its top edge 25 waved. Said projection may conveniently be made by soldering to the front plate a plate 18 having its upper edge formed with the desired profile. When applying the front plate to the back plate of the carrier, the upper edge of the 30 plate 18 is gently forced against the points of the pins, thereby pushing some of them through the folds 16 of the paper and forcing their heads to assume a line similar to the upper profile of the plate 18.

Referring to Fig. 4, the upper part of the carrier is similar to that shown in Fig. 1, and the same reference characters have been accordingly applied thereto but the back plate 10 is integral with a tubular base 19. The base 19 has a flat 35 bottom and may be filled with or contain a weight 20 of iron, lead or other suitable metal so as to enable it to stand steadily on a table.

Referring now to Fig. 5, a carrier, the upper part of which corresponds to that shown in Fig. 1 40 and bears the same reference characters, has the lower portion of plate 10 formed into a box or magazine 21 to hold the remainder of a paper of rows of pins of which the uppermost row projects through a slot in the top of the box and is held 45 between the clamping plates of the carrier. As shown, the magazine is formed to a triangular shape so that it can engage with a dove-tailed groove 22 in the base. Obviously a carrier of the 50 form shown in Fig. 5 could be used without a base if the bottom portion were made heavy enough to enable it to stand steadily without over-balancing. For this purpose the bottom portion may be provided with a sole plate of a suitable metal such as lead or iron.

The back plate 10 of the carrier, together with the magazine for the device of Fig. 5, may be conveniently formed from a stamping of the shape shown in Fig. 6, in which the part 23 forms the back of the magazine 21, the back plate of the 55 carrier rising therefrom. The ends of such magazine are formed by the trapezoidal portions 24, 25 and the front of the magazine is formed by the rectangular portion 26. The blank may be folded along the dotted lines shown, and the edge portions 27, 28 joined together by soldering or brazing, for which purpose portion 27 is a flap provided on one of the end extremities of the blank as indicated by broken lines in the drawings. It will be understood that a carrier and magazine 60

formed from a blank of the shape shown in Fig. 6 must be used with a base which may be of any suitable form such for example as shown in Fig. 5.

It will be understood that the invention is not limited to the precise constructions shown in the drawings and hereinabove described, as various alterations in detail may be made without transgressing the bounds of the invention. The bases of the holders shown in Figs. 1 and 5 may be made of moulded material, such, for example, as the materials formed by the well known phenol-formaldehyde reaction and commonly known by the trade-mark "Bakelite". The carriers in Figs. 1, 4, and 5 are intended mainly for use with a row or rows of pins stuck in papers, such as commonly sold, but papers of pins for refills may be specially made to fit the carriers if desired.

I claim:

1. A holder of the class described comprising spaced apart plates to retain a pin carrying support, means extending from one plate toward the other plate between pins and engageable with said pin-carrying support to retain the support in the holder independently of engagement with the pins, and a support for the lower ends of the pins extending from one of the plates, one of said plates being displaceable relatively to the other plate.

2. A holder according to claim 1 wherein the support for the lower ends of the pins has an uneven upper surface for the purpose specified.

3. A holder of the class described comprising spaced apart plates to retain pins therebetween, and means between the plates on which the lower ends of the pins rest, the pin-engaging surface of said means being uneven whereby the heads of the pins will be disposed at different heights to facilitate removal of the pins.

4. A holder for pins, comprising a carrier including a pair of spaced apart plates adapted to retain in the space between them a paper bearing a row of pins with the heads of such pins projecting clear of the carrier, one of said plates having at its upper edge projections extending towards the other plate between certain adjacent pins and engaging a portion of such paper to hold such paper between the plates without interfering with the ready withdrawal of the pins, one of said plates having an enlargement at its lower edge, and a base having an undercut groove in its upper face to receive said enlargement whereby said carrier is supported in an upright position with the heads of the pins presented uppermost.

5. A holder for pins, comprising a pair of plates spaced apart and adapted to retain in the space therebetween a paper bearing a row of pins with the heads of such pins projecting above the upper edges of said plates, one of said plates having at its upper edge projections extending toward the other plate between adjacent pins and engaging a portion of such paper to hold such paper between said plates when pins are withdrawn from the carrier, one of said plates having its lateral edges turned over to embrace the corresponding edges of the other plate, a base for supporting said carrier, and a separable connection between said carrier and one of said plates.

FRANK OSTRANDER.
